UNITED STATES PATENT OFFICE.

FRED R. STAVA, OF MILROY, MINNESOTA.

SAFETY-GUN.

1,294,186.

Specification of Letters Patent.

Patented Feb. 11, 1919.

Application filed November 29, 1916. Serial No. 134,145.

To all whom it may concern:

Be it known that I, FRED R. STAVA, a citizen of the United States, residing at Milroy, in the county of Redwood and State of Minnesota, have invented certain new and useful 5 Improvements in Safety-Guns, of which the following is a specification.

My invention relates to, and its main object is to provide an attachment for, guns 10 or fire-arms to prevent accidental firing of the cartridge or explosive charge.

I particularly aim to provide means which is normally disposed intermediate the gun hammer and the firing pin to prevent engagement of the hammer with the pin in the event the hammer is accidentally actuated or released, and to employ a means in connection therewith, operable to shift the said means to permit firing.

20 An important object is to provide a gun with the means to prevent accidental firing and which is operable to permit firing by engagement with the shoulder of the gunner or operator and thus operate automatically 25 during the act of positioning the gun.

With the above and additional objects, such as will hereinafter appear in detail, the invention has been embodied in one preferred form as illustrated in the accompanying drawings, wherein:—

Figure 1 is a fragmentary view of a gun shown mostly in section at the stock, and provided with my improvements,

Fig. 2 is a view showing my improvements 35 in top or plan view,

Fig. 3 is a cross sectional view on the line 3—3 of Fig. 1, and

Fig. 4 is a detail perspective of the cam comprising the guard-shifting means.

40 Referring to the drawings, wherein like reference characters designate like or similar parts, a gun is shown fragmentarily but merely by way of example since the specific construction is immaterial as far as my improvements are concerned. The gun shown 45 has a suitable stock at 10 provided with the usual pivoted hammer 11 adapted to engage a firing pin 12 disposed as usual at the rear of the barrel 13. A guard 14 is provided for 50 normal disposition intermediate the hammer 11 and the firing pin 12, that is the guard projects beyond the exposed end of the firing pin toward the hammer, so that if the hammer is accidentally released, it will engage 55 the guard 14 but will not engage the firing pin 12 and accordingly will not fire the car-

tridge or charge. This guard 14 may be of any suitable construction, for instance an arm which is vertically disposed in a guide 15 of any suitable construction. If desired 60 the guide may be dispensed with and the stock 10 cut away to provide a substantially longitudinally disposed hollow or space at 16 within which most of the parts for actuating the guard 14 are disposed. A fulcrum 65 17 extends transversely of the stock and has mounted thereon a lever 18 which is pivoted by means of the pin 20 to the guard 14. This lever is normally maintained raised at its forward end, so that the guard 14 will be 70 in guarding position, by means of a spring 21 which engages and surrounds a lug 22 provided on lever 18 and a lug 23 provided on a plug 24 screwed, as shown, into the stock 10. A lug or shoulder 18' on lever 18 75 limits the rearward pivotal movement of the guard and maintains it in a vertical position. This guard at the forward end is contiguous to the rear end of barrel 13 and it extends backward beyond the exposed end of the 80 firing pin so as to be in the path of movement of the hammer before striking the pin. It will thus be seen that I have provided a means which will prevent accidental discharge of the cartridge or load and thus the 85 arm may be handled with absolute safety.

A suitable means is provided to shift the guard in order that the hammer 11 may engage the firing pin 12 at the desired time. Any suitable means may be employed, but I 90 preferably employ a cam 25 which rests on a flat wall 26 in the hollow 16. This cam has an inclined or cam wall 27 which the rear end of the lever 18 engages so that as the cam is moved toward the hammer, it will tilt the 95 lever 18, raising the rear end and lowering the front end and moving the guard 14 out of the path of movement of the hammer 11. Cam 25 may be fastened to a rod 28 disposed in the hollow 16 and extending from push 100 block or button 29 also mounted in hollow 16. A plate 30 is anchored to the stock and disposed in the hollow 16 and the rod 28 slides therethrough having a crank or angle 31 to abut the plate and limit the outward 105 movement of the rod. A coil expansion spring 32 surrounds the rod 28 intermediate the plate 30 and the block 29, bearing against the same and serving to normally project the push block beyond the butt end of the stock 110 and the crank 31 into engagement with the plate 30. Inward movement of the push

block 29 is limited by the wall 33 of the stock at the hollow. It is important that the push block 29 should extend beyond the butt end since it forms a construction whereby the 5 guard is moved out of the path of the hammer automatically during positioning of the gun for firing.

In use, the gunner or operator manipulates the fire-arm in the usual manner, bringing 10 the stock at the butt end against the shoulder. However, during such movement, the push block 29 first engages the shoulder and it is moved as a result interiorly of the stock, that is within the hollow 16. As a result, 15 the rod 28 and cam 25 are pushed toward the hammer against the tension of spring 32, raising the lever 18 at its rear end against the tension of spring 21 and lowering the guard 14 out of the path of movement of 20 the hammer 11. These parts will remain in this position while the gun stock at the butt end is held against the shoulder and while they are in such position, the firing may be effected. As soon as the gun is moved away 25 from the shoulder, the spring 32 will force the block 29 outwardly and spring 21 will force the lever 18 and guard 14 into normal positions whereby the latter is in the path of movement of the hammer.

30 Since merely the preferred embodiment of the invention has been illustrated and described, it is to be understood that changes in the details of construction may be resorted to without departing from the spirit 35 and scope of the invention.

I claim:—

1. In combination with a fire-arm and the firing means thereof, a guard member to normally render the firing means inactive, a 40 lever to actuate the guard member, a removable plug on the fire-arm, a spring on the opposite side of the fulcrum of the lever to the guard member, and means on the plug and lever to mount said spring.
- 45 2. In combination with a fire-arm and the firing means thereof, a slidable guard member, a lever to which the guard member is

pivoted, means to maintain the guard member against displacement, a slideable rod, means to tilt the lever through movement of 50 the rod, the fire-arm having a hollow space in which the rod is disposed, a plate extending into said space, said rod being mounted by said plate, said rod having a push member, a spring intermediate the push member 55 and plate and bearing against one side of the plate, and means on the rod to abut the other side of the plate.

3. In combination with a fire-arm and its firing means, the stock of the fire-arm being hollow and provided with an abutment wall in the hollow, a bearing disposed within the hollow, a guard means to render the firing means inactive, a slideable means disposed in the hollow to actuate the guard, said slideable means having a head to engage the abutment wall, and said sliding means extending through the bearing and being provided with an abutment to engage the bearing to limit the projection of the slideable 70 member, and a spring interposed between the said head and said bearing.

4. In combination with a fire-arm, and its firing means, a vertically slideable guard member to render said means inactive, a 75 lever member pivoted to said guard member, one of said members at the pivot having a lug engageable by the guard to limit its movement, a spring engaging the fire-arm and the lever to normally maintain it raised 80 at the guard end, a cam engageable by one end of the lever, a rod extending from said cam, a guide plate for said rod mounted on the fire-arm, a push member connected with the rod, and a spring surrounding the 85 rod and engaging the push member and plate.

In testimony whereof I affix my signature in presence of two witnesses.

FRED R. STAVA.
